UNITED STATES PATENT OFFICE

HARRY E. GOSCH, OF NORTH TONAWANDA, NEW YORK, ASSIGNOR TO CREO-DIPT COMPANY INC., OF NORTH TONAWANDA, NEW YORK, A CORPORATION OF NEW YORK

LOCKING DEVICE FOR THE COVERS OF IMPREGNATING TANKS, ETC.

Application filed May 3, 1928. Serial No. 274,783.

This invention relates to an apparatus for removing solid matter from the liquid from precipitating or impregnating shingles or the like, insuring a uniform application of the stain with a paint or similar solution and more particularly to the means for fastening the cover to the tank holding the liquid in which the shingles are dipped.

It is the object of this invention to provide efficient means for holding the cover in place over the dipping tank.

In the accompanying drawings:—

Figure 1 is a fragmentary vertical longitudinal section of the impregnating or dipping tank, showing the same closed and a bundle of shingles supported by the dipping basket within the liquid stain or solution.

Figure 2 is a fragmentary vertical longitudinal section of the impregnating tank, the dipping basket and associated parts, showing the manner of transferring an impregnated bundle of shingles from the dipping tank to the basket of the draining mechanism.

Figure 3 is a horizontal section, on an enlarged scale, taken on line 3—3 Fig. 1.

Figures 4, 5 and 6 are fragmentary vertical sections, on an enlarged scale, taken on the correspondingly numbered lines in Fig. 3.

In the following description, similar characters of reference indicate like parts in the several views of the drawings:—

Although the staining, coating or impregnating device may be variously constructed as to its details, a practical embodiment of the same is shown in Figs. 1—6, and as there shown, this impregnating device is constructed as follows:—

The numeral 30 represents the upright side wall or body of a tank which is adapted to receive the liquid stain 31 or other material with which bundles of shingles 32, or similar goods are to be stained, coated or impregnated.

This tank is preferably provided with a downwardly dished or trough-shaped bottom 33 extending cross-wise of the tank and its upper end is adapted to be opened and closed by a vertically movable cover 34.

In the case of a liquid stain it is desirable to agitate the same in order to maintain it in a thoroughly mixed condition and prevent

Figures 4, 5 and 6 are fragmentary vertical sections, on an enlarged scale, taken on the correspondingly numbered lines in Fig. 3.

In the following description, similar characters of reference indicate like parts in the several views of the drawings:—

Although the staining, coating or impregnating device may be variously constructed as to its details, a practical embodiment of the same is shown in Figs. 1—6, and as there shown, this impregnating device is constructed as follows:—

The numeral 30 represents the upright side wall or body of a tank which is adapted to receive the liquid stain 31 or other material with which bundles of shingles 32, or similar goods are to be stained, coated or impregnated.

This tank is preferably provided with a downwardly dished or trough-shaped bottom 33 extending cross-wise of the tank and its upper end is adapted to be opened and closed by a vertically movable cover 34.

In the case of a liquid stain it is desirable to agitate the same in order to maintain it in a thoroughly mixed condition and prevent

Figure 1 is a fragmentary vertical longitudinal section of the impregnating or dipping tank, showing the same closed and a bundle of shingles supported by the dipping basket within the liquid stain or solution.

Figure 2 is a fragmentary vertical longitudinal section of the impregnating tank, the dipping basket and associated parts, showing the manner of transferring an impregnated bundle of shingles from the dipping tank to the basket of the draining mechanism.

Figure 3 is a horizontal section, on an enlarged scale, taken on line 3—3 Fig. 1.

Figures 4, 5 and 6 are fragmentary vertical sections, on an enlarged scale, taken on the correspondingly numbered lines in Fig. 3.

In the following description, similar characters of reference indicate like parts in the several views of the drawings:—

Although the staining, coating or impregnating device may be variously constructed as to its details, a practical embodiment of the same is shown in Figs. 1—6, and as there shown, this impregnating device is constructed as follows:—

The numeral 30 represents the upright side wall or body of a tank which is adapted to receive the liquid stain 31 or other material with which bundles of shingles 32, or similar goods are to be stained, coated or impregnated.

This tank is preferably provided with a downwardly dished or trough-shaped bottom 33 extending cross-wise of the tank and its upper end is adapted to be opened and closed by a vertically movable cover 34.

In the case of a liquid stain it is desirable to agitate the same in order to maintain it in a thoroughly mixed condition and prevent

annular laterally extending flange 49 arranged at the upper end of the body of the impregnating tank.

In its vertical movements toward and from the seat of the tank body, the cover 34 is preferably guided by means of a plurality of guide shoes 50 formed on brackets 51 secured to the upper side of the cover adjacent to the periphery thereof and slidably engaging the inner sides of a plurality of upright guide rods 52 which have their lower ends secured to brackets 53 projecting laterally from the upper part of the impregnating tank.

The weight of this tank cover and the parts associated therewith are preferably counterbalanced by a counterweight which is connected with one end of a counter-balancing line 56, the opposite end of this line being secured to one of the brackets 51 of the cover.

The raising and lowering of the cover is preferably effected by power and the means whereby such raising and lowering is effected are preferably combined with means whereby the cover is automatically locked in its closed position when lowered upon the body of the tank and is automatically unlocked during the first part of the operation of the mechanism employed for raising the cover.

The motor for thus raising and lowering the cover and also actuating this locking device preferably comprises an upright hydraulic cylinder 59 which is mounted at its lower end on the overhead frame 54 and contains a vertically reciprocating piston 60 which is connected with a piston rod 61 passing through a stuffing box in the lower end of this cylinder and adapted to be raised and lowered by alternately admitting a liquid under pressure into the upper and lower ends of this cylinder and exhausting the same alternately therefrom.

The lower end of the piston rod 61 is attached to a central operating head 69, which latter is capable of moving vertically relatively to the tank head 34 and is guided in this movement by means of a guiding piston 70 moving vertically in a guide cylinder 71 on the central part of the tank head and connected by means of a vertical rod 72 with the lower end of the operating head 69.

On the upper side of the peripheral portion of the tank ring 48 the same is provided with a plurality of abutments or laterally opening loops, each of which preferably consists of a pair of lugs 73 projecting upwardly from a portion of the ring 48 and spaced apart so as to form a slot 74 therebetween, as shown in Fig. 2, a cross bar 75 arranged above the lug 73 and a pair of bolts 76 connecting opposite ends of the cross bar 75 with the upper ends of the lug 73.

Arranged in an annular row above the cover 34 is a group of locking levers each of which cooperates at its inner end with the shifting head 69 and one of the locking

loops of the tank. Each of these locking levers preferably comprises an outer section 77 adapted to engage its outer extremity between the slot 74 and cross bar 75 of one of the locking loops, and an inner section 78 arranged above the outer section 77 and connected by a pivot pin 79 with the adjacent part of the shifting head or hub 69. The outer part of each outer section 77 of this locking lever is guided on the upper marginal part of the cover in a guide loop consisting preferably of upper and lower cross bars 80-81 and a pair of upright posts 82 connecting opposite ends of the cross bars 80-81 with each other and with the adjacent part of the cover 34, as best shown in Fig. 4.

The outer and inner sections 77-78 of each locking lever are preferably resiliently connected with each other so that at times they practically form one integral or rigid lever but at other times are capable of yielding one relatively to the other so that each locking lever is capable of cooperating individually in the most effective manner with its companion locking loop 74-75 on the tank during the operation of locking and unlocking the cover thereof.

This yielding connection between the members 77-78 of each locking lever is preferably effected by means of a horizontal pivot pin 83 passing through the inner part of each outer lever section 77 and a pair of lugs 84 depending from the central part of the companion inner lever section 78, and a pair of upright tension rods 85 arranged on opposite sides of the lever sections 77-78 and each passing with its central part through a guide eye 86 on the adjacent part of the inner lever section 78 and connected at its lower end with a laterally projecting bracket 87 on the adjacent part of the outer locking lever section 77, a cross bar 88 connecting the upper ends of the tension rods 85, and tension springs 89 each of which surrounds the upper part of one of the tension rods 85 and bears at its upper and lower ends against the underside of the cross bar 88 and the guide eye 86 of the inner locking section 78 through the medium of washers 90-91.

When the tank cover is in its lowered position or closed position and the packing 46 thereof engages with the seat 47 of the tank, the shifting head or hub 69 is in its lowered position and the sections 77-78 of each locking lever are in a substantially horizontal position in which the overlying parts of these lever sections engage with each other in parallelism and are yieldingly held in this position by the springs 89. At this time the outer extremities of the lever sections 77 are also projected laterally outward beyond the guide loops 80, 81, 82 and into the locking loops 74, 75 so as to engage with the undersides of the several cross bars 88 and thereby

lock the cover in its closed position against the seat on the upper end of the tank.

This projecting of the outer sections of the locking levers with the locking loops 5 74—75 on the tank occurs during the last portion of the downward movement of the shifting head or hub 69 after the cover rests on the seat of the tank.

During the initial part of the upward movement of the shifting head or hub 69 the same moves independently of the cover 34 so as to incline the sectional locking levers 77, 78 and cause the outer ends of the lever section 77 to be first withdrawn from the locking loops on the tank, so that the cover 34 is released and thereafter the latter can be raised from the upper end of the tank, as shown in Fig. 2.

If, during the last portion of the downward movement of the shifting head 69, the outer section 77 of one or more of the locking levers should reach the end of the locking movement before others, breakage of such levers is prevented by the continued downward movement of the shifting head 69 due to the elastic connection provided by the springs 89 between these lever sections 77, 78.

A similar deflection of the two sections 77, 78 of each locking lever occurs when the weight of the cover 34 and the parts suspended therefrom are raised by the hoisting mechanism, and causes the weight of these suspended parts to be distributed uniformly among these levers inasmuch as each of these levers by this means can adapt itself to any slight inaccuracies in the fitting of the same to the parts with which the same cooperates. This flexed position of the inner and outer sections of the locking levers when lifting the cover of the impregnating tank is represented in Fig. 2, but a similar relation of these lever sections occurs if some of the inner sections should be pressed downwardly farther than the corresponding sections of other levers during the operation of closing the cover over the tank body.

In order to cause the outer sections of the locking levers to bear with substantial uniformity against the upper bars 75 forming parts of the locking loops on the tank body, these bars may be raised or lowered by tightening or loosening the bolts 76 whereby these bars are connected with the lugs 73.

The bundle or bundles of shingles which are to be impregnated or coated with stain or other liquid are preferably supported on the underside of the cover of the tank so that upon closing and opening this cover the material under treatment will be lowered into the liquid and raised out of the same. For this purpose a carrier is provided on the underside of the cover, which preferably has the form of a basket and this basket in the preferred construction, as shown in the drawings, comprises two upright, longitudinal, tight side

walls 92, and a plurality of horizontal connecting rods 93 extending transversely across the space between the upper and lower ends of these side walls and connected at their opposite ends thereto. The upper ends of the side walls of this basket are pivotally connected about midway of their length to the underside of the cover 34 so that this basket

is capable of swinging in a vertical plane lengthwise of the apparatus, this connection consisting preferably of horizontal pivot pins

94 mounted on the inner sides of the upper central parts of these walls 92 and passing

through brackets 95 which are secured to the

underside of the tank cover 34, as best shown

in Figs. 1 and 2. Between the lower connecting rods 93 of the basket, the latter is pro-

vided with a row of transverse rollers 96 which are adapted to engage with the under-

side of the bundles of shingles and permit of

more easily moving these bundles into and

out of the basket.

The pivot pins 94 are preferably arranged somewhat in rear of the center of gravity of

this bundle-receiving basket so that when

free the basket will tend to drop by gravity

under its own weight and that of the bundle

of shingles therein, so that the open work or

grate-like bottom of the basket will incline

forwardly toward the front end of the basket.

This tilting movement is, however, limited by means of stops 97 arranged on the upper

rear parts of the basket side walls 92 and

adapted to engage with the underside of the

tank cover, as shown in Fig. 2. The bundle of

shingles 32 or other articles to be stained or

impregnated is introduced by the operator

into the basket at the rear end thereof, which

is constantly open for this purpose.

After one or more bundles of shingles have

been introduced into the basket from the rear

end thereof, the latter is turned so that its

bottom is arranged horizontally, in which

last mentioned position the basket is lowered

with its load of bundles of shingles into the

treating liquid within the tank. In order to

hold the basket in this normal position in

which its bottom is arranged horizontally, a

latching device is provided which in the pres-

to permit of depressing its front end and inclining the bottom thereof for the purpose of discharging the contents of the basket, this may be effected manually by the attendant who raises the catches 98 out of engagement from the stop lugs 99 whereupon the basket will be free to drop at its front end and cause its bottom to incline forwardly, as shown in Fig. 2.

The discharge of the bundle from the basket is effected from the front end thereof, which latter may be opened and closed by means of a gate 104 which preferably consists of a plate of metal pivoted at its lower end by means of pins 105 to the side walls of the basket so that this gate can either be raised into its upright operative position across the front outlet of the basket, as shown in Fig. 1, or the same can be swung forwardly and downwardly into a position in which it is on a line with the bottom of the basket, as shown in Fig. 2, preparatory to discharging the treated bundle of shingles or other material from the basket of the impregnating device to the devices which subsequently operate upon the bundle for draining the excess liquid attached thereto.

Various means may be provided for holding the outlet gate of the basket in its upright operative position but it is preferable to employ for this purpose the means which are shown in the drawings and which consist of a vertically swinging catch 106 pivoted at its rear end by means of a horizontal transverse pin 107 to one of the walls of the basket adjacent to the upper front corner thereof and engaging the nose at its front end with the upper edge of the basket gate, as shown in Fig. 1.

When the basket containing a load of shingles is lowered into the tank, the latter contains a batch of liquid stain or other fluid sufficient to cause the bundles of shingles to be submerged therein when the cover is closed.

After the basket has been thus lowered with its load into the batch of liquid stain within the tank and the cover has been securely fastened in place so as to form an air tight joint between the same and the body, a vacuum is produced within the tank so as to rarify the air therein and withdraw all or part of any moisture that may be present in the tank or within the pores of the shingles.

After the bundle of shingles or other material has been submerged in the impregnating liquid, the interior of the tank is subjected to air pressure so as to drive the liquid stain or other fluid into the pores of the shingles or the like under treatment and when this impregnating pressure has been maintained for a sufficient length of time to suit any particular requirement, this pressure is discontinued.

After the air pressure in the tank has been

discontinued the cover 34 of the tank is unlocked and raised together with the bundles of shingles supported in the basket thereof, and this material is then discharged from the basket through the outlet at the front end thereof to a draining device, and a new batch of shingles or other material is introduced into the basket through the rear end thereof, and the front gate 104 is closed preparatory to again submerging the basket and its contents into the liquid stain within the impregnating tank in the manner previously described.

Pressure within the tank and the exhaustion of air for creating a vacuum therein may be effected in various ways but preferably by means which comprise a pressure pipe 112 connected with a pressure pump or air compressor of any suitable character, a vacuum pipe 113 connected with a vacuum pump or device of any suitable character, and a branch pipe 114 connecting with said pressure and vacuum pipes and communicating with a stand pipe opening into the upper end of the tank.

The pressure pipe 112 contains a three-way valve 118 whereby the branch pipe 114 may be connected either with a pipe 119 leading to the atmosphere or with the pressure pipe 112; and a three-way valve 120 is also arranged in the vacuum pipe 113 whereby the branch pipe 114 may be either connected with a pipe leading to the atmosphere or with the vacuum pipe 113.

After the cover of the tank has been raised to its highest position with the basket on the underside thereof still in its normal upright position and carrying a lot of shingles or like articles which have just been treated with the liquid in the tank, as shown in Fig. 1, the catches 98 on the cover are moved out of engagement from the catch lugs 99 on the side walls of the basket. When this is done the basket is tilted forward by the preponderating weight in its front part together with the load therein until the stop 97 on the rear part thereof engages with the underside of the tank cover 34, as shown in Fig. 2.

After the basket has been thus tilted, the operator releases the catch 106 from the upper edge of the door 104 thereby permitting the latter to be lowered from the upright position shown in Fig. 1 to the forwardly inclined position shown in Fig. 2. When this is done the bundles of shingles or other articles may be moved forwardly out of the basket along the bottom thereof and the inner side of the inclined gate and discharged to a device whereby the excess of liquid stain or similar fluid is removed from the shingles. The movement of the bundles of shingles or the like out of the basket at this time is facilitated by the rolling support formed by the rollers 96 at the bottom of a basket and

the comparatively free movement of the bundles over the gate 104 which is coated with the treating liquid and therefore acts somewhat in the nature of a lubricant which permits the bundles to slide easily over this gate.

After the bundle has been thus discharged from the basket of the dipping or impregnating device to the device which drains the excess of liquid from the bundles, the operator again lifts the gate 104 and locks the same in its upright operative position on the basket, and the latter is again turned into its normal upright position and held there by means of the catches 98 preparatory to receiving another charge of shingle bundles which are to be dipped into the liquid of the tank.

The draining device whereby the excess or surplus liquid is removed from the bundles of shingles is arranged close to the front side of the dipping or coating device so that the transfer of the shingle bundles may be effected directly from the dipping device to the draining device without the use of any intermediate conveying mechanism, thereby rendering the apparatus, as a whole, very compact and also facilitating the operation of staining the shingles and reducing the cost of production.

This draining device may be of any suitable construction and is indicated generally by the reference characters 128, 139 and 140 in Fig. 2 which form parts of the rotary draining cage or basket.

It will be apparent from the foregoing description and illustrations that this apparatus permits of expeditiously and conveniently dipping bundles of shingles or like materials, in a liquid stain or other fluid with which the same are to be treated and then transferred and operated upon by the draining mechanism whereby the excess liquid is recovered, and that these operations are performed with a minimum amount of labor and expenditure of power and also without occupying an undue amount of space, thereby enabling work of this character to be performed very efficiently and economically.

I claim as my invention:—

1. An apparatus for the purpose described, comprising a tank adapted to contain liquid for treating articles and having an inlet at its top for the passage of said articles; a cover movable toward and from said inlet; and means for locking said cover on said tank, comprising a plurality of abutments arranged on said tank around the inlet thereof, a vertically movable lifting head arranged above the cover, and a plurality of locking levers pivotally mounted on said cover and each connected at its inner end with said head and adapted to engage its outer end with one of said abutments, each of said levers consisting of a plurality of sections, and

means for yieldingly holding said sections together.

2. An apparatus for the purpose described, comprising a tank adapted to contain liquid for treating articles and having an inlet at its top for the passage of said articles; a cover movable toward and from said inlet; and means for locking said cover on said tank, comprising a plurality of abutments arranged on said tank around the inlet thereof, a vertically movable lifting head arranged above the cover, a plurality of locking levers pivotally mounted on said cover and each connected at its inner end with said head and adapted to engage its outer end with one of said abutments, each of said levers consisting of a lower outer section, an inner upper section, a pivoted connection between said sections, tension rods arranged on opposite sides of said sections and connected with one of them, and springs interposed between said rods and the other section.

In testimony whereof I hereby affix my signature.
